SAFETY DEVICE

Charles W. Wyman, Claremont, N. H., assignor to
 Sullivan Machinery Company, a corporation
 of Massachusetts

Application December 17, 1931, Serial No. 581,709

17 Claims. (Cl. 172—36)

This invention relates generally to mining machines of the electric motor propelled type, and more particularly to the electrical apparatus of such machines. From another aspect it relates 5 to drain devices.

The injurious effect of oil upon the insulated windings of electric motors is well known. In mining machines of ordinary construction, the possibility of damage from such causes is quite 10 substantial, and in machines in which portions of the gearing run in oil and which comprise motors which are adapted to be tilted or rotated in the changing of the plane of cut, the chance of damage from this source is substantially increased. Machines are, moreover, often used in 15 wet places, and should any water secure access to the motor spaces, its discharge would be important.

The provision of drainage arrangements would 20 not be so difficult were it not for the fact that in many mines explosive gases are present and ignition of these gases within the motor spaces might be followed by escape of the flames through the drainage passages, with resultant 25 danger of great damage to life and property within the mine.

A primary object of the invention is to provide improved means for effecting drainage of electric motor casings or other chambers containing 30 electrical circuit making and breaking apparatus, and combining with efficient drainage, complete protection against the ignition of inflammable gases surrounding such chambers. Other objects and advantages of the invention 35 will subsequently appear.

In its general aspect, the invention includes improved means forming a drain vent and associated means providing for the effective prevention of the escape of flame from the space 40 to be drained. In a preferred form, the two functions may be combined in a drain plug which houses within it structure forming a tortuous passage, preferably dividing the gases into a thin stream and repeatedly reversing their 45 direction of flow, for extinguishing and cooling any ignited gases which may have occasion to pass therethrough, the same passages which extinguish and cool the gases also serving to drain any liquid which may be within the spaces to be 50 drained and protected. Obviously, the cooling devices need not be contained, however, in a detachable plug, but may be disposed in a bore in the walls of the motor or controller chamber, or the like.

55 A peculiarly effective action may be obtained

by causing the gases to pass in a very thin stream between suitable relatively cool surfaces, the while repeatedly sharply reversing the flow of the stream and subjecting it to eddies.

In the accompanying drawing, in which an 60 illustrative embodiment of the invention is shown,—

Fig. 1 is a fragmentary view, in side elevation, with parts broken away, of a mining machine constructed in accordance with the illustrative form of the invention. 65

Fig. 2 is a section through the illustrative form of drain plug.

Fig. 3 is a developed view of the parts housed within the illustrative form of drain plug. 70

Referring to the drawing, 1 is a mining machine frame which includes a motor 2 and which is mounted by means not shown, for rotation about the axis of the motor shaft 3. The motor comprises a casing 4 within which a rotor 5 and field 6 are enclosed. 75

The commutating devices of the motor are not shown, being at the right hand end of the motor 2, but it will be evident that should combustible gases secure access to the interior of the casing, these might be ignited by a spark at the commutator, or if a coil should be burned out due to overload, or should grounding occur within the casing 4. At the opposite ends of the casing 4 are frames 7 and 8, each of which 80 houses lubricating mechanism, and lubricant is, despite the best structural precautions, likely to enter the motor casing 4. Moreover, in wet mines, water may secure access to the interior of the casing 4. 85

To drain the casing shown, which is capable of being turned over, it is desirable, and indeed important, to provide a plurality of drain devices one of which may be at the bottom of the casing, and effective, irrespective of the position of the 95 motor. Two drains, indicated generally 11 and 12, are therefore provided, one on the top and the other on the bottom of the casing. As the structure of these drains is alike, but one will be described.

As illustrated, each drain device comprises a plug 15, herein shown as threaded at 16 for connection to the casing 4. The plug 15 is traversed by a longitudinally extending passage 17, and at the inner end of the plug the passage is made flaring, as at 18, to facilitate drainage, while the outer end of the passage is expanded to form an enlarged chamber 20. 105

Advantageously, a screen 21 may be located by any suitable means, as a groove 22, into which 110

its edges may be sprung, at or near the mouth of the tapered portion 18 of the passage 17, for the purpose of preventing solid matter of any kind from entering the plug.

- 5 Within the chamber 20 are located flame-proofing devices, generally designated 25. A wide variety of such devices may obviously be used, the essential features being the restriction of the escape of gases which might become ignited within the motor casing in such manner that they will be cooled and extinguished before reaching the outlet of the drain plug. In order not to defeat the drain function of the plug, however, some structures will be found preferable to others. An arrangement which has proved highly effective in test includes a number of thin discs 27 each having a segment thereof cut away at 28 to provide a chordal edge 29, these discs being arranged with the chordal edges of each pair of adjacent discs parallel but at opposite sides of the axial line of the discs, and successive discs being spaced by members 30 so narrow radially that a substantial segmental opening 31 remains between the chordal edge 29 of each disc 27 and the inner periphery of the coaxial contacting annuli 30. One suitable material for the discs and annuli, which may be made of any substance which will not be injured by exposure to oil and water and acids such as may be encountered in coal mines, is hard rolled copper; this is sufficiently strong and heat resistant to withstand conditions resulting from possible explosions of gases within the motor frame, and is a good heat conductor. Satisfactory annuli and discs both have been made in sizes not over $1\frac{1}{2}$ inches in diameter from .0125 inch hard drawn copper stock; and depending upon the number of discs to be used and the cross sectional area of the passages, a substantial variation in the thickness of the stock may be permitted. For a cross sectional area of the passage 17 of $\frac{5}{8}$ inch, I have found good results from the use of twenty-one washers and twenty discs of the thickness mentioned, each having a diameter of $1\frac{1}{8}$ inches and with the inner diameter of the annuli about three-fourths of their outer diameter and the discs 27 cut so that the distances from the center of their edges 29 to the most remote point in their opposite edges was substantially the same as the inner diameter of the annuli. For smaller passages 17, a smaller number of discs and annuli is satisfactory, and a larger passage would be provided to maintain an equal margin of safety with an increased number.

The discs and annuli may be held in place by any suitable means, as by clamping between a shoulder 33 at the inner end of the chamber 20 and a shoulder 34 formed by peening over a flange 35 at the outer end of the chamber.

Referring particularly to Figs. 2 and 3, it will be noted that with the discs and annuli most advantageously assembled in a stack in the chamber 20, with a disc intermediate each pair of annuli, there is provided a tortuous passage including segmental portions 36, opening axially of the drain plug and alternately at diametrically opposite sides of the plug, and also including parallel wide, but very shallow, portions 37, in adjacent ones of which fluid flow takes place in opposite directions. The flow area of each segmental portion 36 is, in the illustrative embodiment, many times that of each shallow portion 37. The thinness of the stream of gases

which can flow through a passage so constructed insures cooling and extinguishing of any burning gases which might start to flow through the plug. The sharp reversals of flow at the portions 36 create eddies which retard flow of gases seeking to rush outward, and also by the eddying, baffling action give rise to a most effective extinguishing action. The use of copper or similar discs provides excellent cooling of the gases and further promotes flame extinguishing action. Obviously, oil and water which may secure access to the interior of the motor casing may flow out through the tortuous passage and maintain the casing constantly drained.

While I have in this application specifically described one form which my invention will assume in practice, it will be understood that this form is shown for purposes of illustration and that the invention may be modified and embodied in various other forms without departing from its spirit or the scope of the appended claims.

What I claim as new and desire to secure by Letters Patent is:

1. A flame-proof drain device comprising means forming a chamber communicable with a space to be drained, and means in said chamber forming a passage providing for drainage by gravity and comprising a plurality of thin superimposed portions of a length and width many times their thickness and in which flow is in opposite directions.

2. A flame-proof drain device comprising means forming a chamber communicable with a space to be drained, and means therein for cooling and extinguishing gases which may flow therethrough and providing for gravity drainage of liquid including means forming a plurality of substantially parallel thin passage portions communicating with each other to form a baffled discharge and arranged to prevent entrapping of liquid therein.

3. A flame-proof drain device comprising means forming a chamber communicable with a space to be drained, and means therein for cooling and extinguishing gases which may flow therethrough including means forming a plurality of thin, parallel horizontal passage portions communicating with each other to form a passage in whose successive parallel portions flow is in opposite directions.

4. A flame-proof drain device comprising means forming a drain passage, and, between the ends thereof and extending transversely with respect thereto, a stack composed of alternate discs and annuli, said discs having segments cut away to permit flow between the spaces surrounded by successive annuli and being disposed with the cut away portion of each disc adjacent uncut portions of its neighbors.

5. A flame-proof drain device comprising means forming a drain passage, and, between the ends thereof and extending transversely with respect thereto, a stack composed of alternate discs and annuli, said discs having segments cut away to permit flow between the spaces surrounded by successive annuli and being disposed with the cut away portion of each disc diametrically opposite the cut away portions of its neighbors.

6. A flame-proof drain device comprising means forming a drain passage, and, between the ends thereof and extending transversely with respect thereto, a stack composed of thin alter-

- 50 nate discs and annuli, said discs having segments cut away to permit flow between the spaces surrounded by successive annuli and being disposed with the cut away portion of each disc adjacent uncut portions of its neighbors. 5
- 55 7. A flame-proof drain device comprising means forming a drain passage, and, between the ends thereof and extending transversely with respect thereto, a stack composed of thin, metallic, alternate discs and annuli of high heat conductivity, said discs having segments cut away to permit flow between the spaces surrounded by successive annuli and being disposed with the cut away portion of each disc diametrically opposite the cut away portions of its neighbors. 10
- 60 8. In combination, a motor casing, and flame-proof drainage devices therefor arranged at the bottom thereof and providing a drain passage containing sharp reversals in direction. 15
- 65 9. In combination, a casing enclosing electrical apparatus, and drainage devices therefor positioned to preclude rise of liquid level in said casing to a substantial height and providing a relatively wide, thin drain passage containing sharp reversals in direction. 20
- 70 10. In combination, a motor casing disposable in a plurality of positions, and flame-proof drainage devices arranged to drain said casing in a plurality of positions. 25
- 75 11. In combination, a casing containing electrical apparatus, a drain opening from said casing adjacent the bottom thereof, and means forming a tortuous passage through which drainage must pass in a flattened, frequently reversed stream. 30
- 80 12. A flame-proof drain device comprising means forming an enclosure to provide a drain passage, and, between the ends thereof and arranged with its axis extending longitudinally of the drain passage, a stack composed of alternate discs, and annuli, each having plane parallel opposite faces and of a thickness a very small percent of their respective diameters, said discs having segments cut away to permit flow between the spaces surrounded by successive annuli and being disposed with the cut-away portion of each disc opposite the cut-away portion of the adjacent disc. 35
- 85 13. A flame-proof drain device comprising means forming an enclosure to provide a drain passage, and, between the ends thereof and arranged with its axis extending longitudinally of the drain passage, a stack comprised of alternate discs and annuli, each having plane parallel opposite faces and of a uniform thickness a very small percent of their respective diameters, said discs having segments cut away to provide relatively large eddy chambers and to permit flow between the spaces surrounded by successive annuli and being disposed with the cut-away portion of each disc opposite the cut-away portion of the adjacent disc. 40
- 90 14. A flame-proof drain device comprising means providing a chamber and baffle and cooling means therein providing a plurality of very thin relatively wide flow passages extending alternately in opposite directions and connecting eddy chambers of many times the flow area of said flow passages, each eddy chamber communicating directly with and connecting but a single pair of said flow passages. 45
- 95 15. In combination, a motor casing, and flame-proof drainage devices therefor having means providing a drain passage containing sharp reversals of direction and providing for alternate downward and horizontal flow exclusively. 50
- 100 16. In combination, a casing providing a chamber enclosing electrical apparatus, and drainage devices therefor for preventing substantial trapping of liquid in the chamber, said drainage devices providing a relatively wide, thin drain passage comprising portions providing sharp reversals in direction and connecting relatively straight portions positioned to permit natural flow by gravity of liquid delivered thereto. 55
- 105 17. In combination, a motor casing disposable with different portions of the surface thereof in lowermost position, and a plurality of flame-proof drainage devices respectively arranged to drain said casing in different positions thereof. 60
- 110 115 120 125 130 135 140 145 150
- 50 55 60 65 70 75
